UNITED STATES PATENT OFFICE.

WILLIAM G. ROOME, OF JERSEY CITY, NEW JERSEY.

RAILWAY-SIGNAL.

SPECIFICATION forming part of Letters Patent No. 558,565, dated April 21, 1896.

Application filed November 17, 1893. Serial No. 491,255. (No model.)

To all whom it may concern:

Be it known that I, WILLIAM G. ROOME, of Jersey City, in the county of Hudson and State of New Jersey, have invented a certain new and useful Improvement in Railway-Signals, of which the following is a specification.

I will describe my improvement in detail, and then point out the novel features in the claims.

In the accompanying drawings, Figure 1 is a diagrammatic view of a portion of a railway and appurtenances embodying my improvement. Fig. 2 is a diagrammatic view illustrating a modification of the main circuit. Fig. 3 is a diagrammatic view illustrating a modification of the circuits. Fig. 4 is a diagrammatic view illustrating a modification of the circuits. Fig. 5 is a diagrammatic view of a single-track railway having two systems of signaling devices for protecting in different directions. Fig. 6 is a diagrammatic representation of two tracks upon which trains are intended to run in the same direction, and they are shown as combined with appurtenances embodying my improvement. These two tracks are intended to form part of a four-track railroad. Fig. 7 is a diagrammatic view illustrating the application of my improvement to railroad-tracks crossing each other.

Similar letters of reference designate corresponding parts in all the figures.

Referring first to Fig. 1, A designates a railway-track of ordinary or any suitable construction. It may be regarded as one of the tracks of a double-tracked railroad. B designates an arbitrary representation of a dynamo-electric machine. The machine I use may be of any desired type. This dynamo is intended to supply current for certain signaling devices employed in a block system. The track A comprises a number of sections a' a^2 a^3 . The section a' may be regarded as a section extending from a depot or station. The rails comprised in each track-section are intended to be made continuous electrically. This may be done by means of fish-plates, chairs, or other devices made of metal and electrically connecting the ends of abutting rail-sections. A simple way of connecting adjacent rail-sections comprised

in the track-section is to fasten the ends of a wire between each pair of adjacent rail-sections. The rails comprised in each track-section are in this example of my invention electrically independent of those comprised in any other track-section. Their electrical independence may be secured by employing chairs or fish-plates of insulating material, such as wood, between the rails comprising one track-section and those comprised in each adjacent track-section.

In my improvement I use what may be regarded as a main circuit comprising all the signals and also protecting devices if such be used, and I also use a track circuit or circuits. In each track-circuit the rails of one of the track-sections is comprised.

I will first describe the main circuit and its appurtenances.

C' designates a wire leading from one pole or electrode of the dynamo-electric machine B to the ground. As here shown it is represented as connecting with a ground-plate G' . C^2 designates another wire extending from the other pole or electrode of the machine. This wire extends to a point where the main circuit branches, one branch C^3 extending to one terminal or contact-point of a resistance device E and the other branch C^4 extending to one end of the coil of an electromagnet s' belonging to a danger-signal S' . The electromagnet s' will preferably be of the solenoid type or one capable of producing a long range of movement. The signal S' is represented as consisting of a lever fulcrumed between its ends on a pin t' . One end is provided with a signal-board or other signal contrivance and the other is connected to the armature of the magnet. The magnet represented being of the solenoid type; its armature is consequently made in the form of a movable core. A weight u' is combined with the magnet-armature and signal-lever for moving the latter in the opposite direction to that in which it will be moved by the magnet. It is intended that the magnet shall normally influence the signal and hence set it and maintain it at the position indicative of safety, and that whenever the magnet is deenergized the weight shall set the signal to the position indicative of danger. When the signal-lever is tilted out of horizontal position, it indicates safety, and to indicate

danger it is adjusted to a horizontal position. From the other end of the coil of the electro-magnets s' a wire C^5 extends to a circuit-changer H' , here shown as consisting of a lever fulcrummed at one end to a pin h' and having at the other end a contact-piece which is adapted to coat with the contact-piece i' , a magnet I' being employed for maintaining the lever H' in contact with the contact-piece i' and a spring J' being employed to adjust the lever H' , so as to withdraw it from the contact-piece i' whenever the magnet I' is deenergized.

It may be remarked in passing that the magnet I' is not in the main circuit, but in a track-circuit. From the contact-piece i' a wire C^6 extends to one end of the coil of an electromagnet s^2 belonging to a signal S^2 . The signal S^2 and the electromagnet s^2 may be exactly like the corresponding parts of the signal S' already described and similarly combined with a weight. The other end of the coil of the electromagnet s^2 is connected to a wire C^7 , which is united with a wire C^8 , extending from the resistance device E . From the wire $C^7 C^8$ a wire C^9 extends. Before proceeding further I may remark that the signal S' is intended to be a cautionary signal and the signal S^2 a danger-signal. Owing to this it is desirable that the signal boards or devices of these two signals should be distinctive either in shape or color or both. I have indicated a difference in shape and would add that ordinarily to conform to existing practices the signal board or device of the cautionary signal S' would be green and that of the danger-signal S^2 red. The signal S' would be located adjacent to the first section a' of the track A at a considerable distance from the second section a^2 of said track. The signal S^2 will preferably be located at about the junction of the two sections $a' a^2$.

In order that the function of the circuit-changer H' may be readily understood, I will remark here that the magnet I' has the two ends of its coil connected by wires with the rails comprised in the track-section a^2 . The details of this local or track circuit, which comprises the rails of the track-section a^2 and the coil of the magnet I' , and the manner of supplying the same with current I will presently explain. Obviously while there is no train, car, or locomotive upon the track-section a^2 the magnet I' will be energized and the circuit-changer H' will be caused to impinge upon the contact-piece i' , thus continuing the signal-circuit. As the electromagnets $s' s^2$ of the signals $S' S^2$ will be energized, these signals will be maintained at the positions indicative of safety. This will be the normal condition of the signals, and reference to the drawings will show that is the condition in which they are illustrated, there being no train, car, or locomotive represented as located upon the track-section a^2 . I may add as a further explanation of the conditions in which the track-sections $a' a^2$ and their appurtenances are illustrated that the

engineer of a train passing over the track-section a' will be informed first by the cautionary signal S' long before his train reaches the second track-section a^2 , and later by the danger-signal S^2 at the time his train arrives at the second track-section a^2 , that there is no train upon the second track-section a^2 , and consequently that he may proceed in safety. The resistance device E in that branch of the main circuit comprising the wires $C^3 C^8$ is employed to make this circuit branch approximately correspond in resistance with the other branch of the main circuit consisting of the wires C^4, C^5, C^6 , and C^7 and comprising the coils of the magnets $s' s^2$ belonging to the signals $S' S^2$ and the circuit-changer H' . From the wire C^9 a wire C^{10} extends to one of the coils of a transformer K' . This transformer may be of any suitable construction comprising low and high potential coils. It may be remarked here that if a direct-current dynamo be used a dynamotor or direct-current transformer (sometimes called a "motor-dynamo") would be preferable. In other cases the ordinary circuit alternating-current transformer would suffice. As it is employed to furnish current of low potential to the track-circuit comprising the rails of the track-section a^2 , the wire C^{10} is connected with one extremity of the high-potential coil of the transformer, and wires are extended from the extremities of the low-potential coil of the transformer to the ends of the rails comprised in the track-section a^2 . From the other extremity of the high-potential coil of the transformer a wire C^{11} extends. From the wire C^9 , at a point whence the wire C^{10} extends from it, a wire C^{12} extends to one end of the coil of an electromagnet belonging to a signal S^3 . This is a cautionary signal intended to indicate to the engineer of a train, car, or locomotive passing along the second track-section a^2 whether any train, car, or locomotive is located upon the third track-section a^3 . This signal may be like the signal S' , fulcrummed in the same manner to a pin t^3 and combined with an electromagnet s^3 and weight u^3 , like the corresponding appurtenances of the signal S' . From the other end of the coil of the electromagnet s^3 of the signal S^3 a wire C^{13} extends to a circuit-changer H^2 . This circuit-changer consists of a lever corresponding with that forming the circuit-changer H' , is similarly fulcrummed at one end to a pin h^2 , and is adapted at the other end to coat with a contact-piece i^2 . This lever is combined with a spring J^2 and an electromagnet I^2 . The magnet I^2 has its coils connected with the rails comprised in the track-section a^3 .

From the contact-piece i^2 a wire C^{14} extends to one end of the coil of an electromagnet s^4 belonging to a signal S^4 . From the other end of the coil of the magnet s^4 a wire C^{15} extends. The wire C^{15} joins the wire C^{11} , and from these two wires the main circuit is continued by wire C^{16} . The signal S^4 is intended to be a danger-signal like the danger-signal S^2 and

capable of indicating to the engineer of a train, car, or locomotive reaching the end of the second track-section a^2 whether any train, car, or locomotive is located upon the third track-section a^3 . This signal S^4 is fulcrumed to a pin t^4 and combined with a weight u^4 . Normally the magnet I^2 will hold the circuit-changer lever H^2 against the contact-piece i^2 ; but whenever a train, car, or locomotive is located upon the track-section a^3 it will form a short circuit between the parallel rails of this track-section and so deenergize the magnet I^2 , whereupon the spring J^2 will move the circuit H^2 away from the contact-piece i^2 and deenergize the magnet s^3 of the cautionary signal S^3 and the magnet s^4 of the danger-signal S^4 . This is the condition of things illustrated in connection with the third track-section a^3 and the signals appertaining thereto, I being an arbitrary representation of a train, car, or locomotive. The engineer of a train, car, or locomotive passing while this condition of things exists along the second track-section a^2 will be informed by the cautionary signal S^3 that a train, car, or locomotive is located upon the third track-section a^3 , and will thus receive such information before arriving at the beginning of the third track-section a^3 , when it will be seen that he will again receive this information from the danger-signal S^4 when he arrives at the beginning of the third track-section a^3 .

Obviously the electrical resistance of that branch of the main circuit consisting of the wires C^{10} and C^{11} , including the high-potential coil of the transformer K' , should be made by properly proportioning the transformer or by any other means to approximately correspond with the other branch of the main circuit consisting of the wires C^{12} C^{13} C^{14} C^{15} and including the coils of the magnets s^3 s^4 and the circuit-changer H^2 . The main-circuit wire C^{16} extends to one extremity of the high-potential coil of the transformer K^2 . From the other end of this coil a wire C^{17} extends. The extremities of the low-potential coil of the transformer K^2 are connected with the parallel rails of the track-section a^3 near their forward extremities and thus a current of low potential is furnished to the track-circuit comprising the rails of this track-section a^3 , together with the coil of the electromagnet I^2 . The wire C^{17} will extend to the appurtenances of another track-section in advance of the track-section a^3 . At the end of the system connection will be made with the ground. To illustrate this I have shown the wire C^{17} extending to a ground-plate G^2 . It will be seen that in this example of my improvement there is a main circuit comprising the magnets of all the signals and furnishing them with electricity from a common source, also that there are a number of track-circuits which are practically independent of the main circuit and are supplied with electricity of low

potential, so as to render it practicable to utilize the rails of the several track-sections. These track-sections control the signals.

In Fig. 2, A designates a track comprising sections a^1 a^2 . B designates a dynamo having one pole or electrode connected by a wire C' with a ground-plate G' and having its other pole or electrode connected by a wire C^2 with one of the coils of the transformer K^3 . From the other extremity of the coil of this transformer a wire C^{18} extends to one extremity of the high-potential coil of a transformer K' . From the other extremity of this coil a wire C^{19} extends to a ground-plate G^2 . The extremities of the low-potential coil of the transformer K' are connected with the adjacent ends of the rails comprised in the track-section a^2 , the other ends of these rails being connected with the extremities of the coils of the magnet I' . S' designates a cautionary signal arranged adjacent to the track-section a^1 at some distance from the track-section a^2 . It is pivoted between its ends to a pin t' and combined with a weight u' as well as with a magnet s' . S^2 designates a danger-signal pivoted between its ends to a pin t^2 and combined with a magnet s^2 and a weight u^2 . As this figure illustrates a single-track railroad requiring signals for trains running in both directions, I employ signals S^5 S^6 on the opposite side of the track from the signals S' S^2 . The signal S^5 is fulcrumed to a pin t^5 and combined with a magnet s^5 and a weight u^5 . The signal S^6 is fulcrumed on a pin t^6 and combined with a magnet s^6 and a weight u^6 . From one end of that coil of the transformer K^3 which is not connected with the wires C^2 C^{18} a wire C^{20} extends to one end of the coil of the magnet s' . From the other end of the coil of this magnet a wire C^{21} leads to a circuit-changer H' , which is combined with the magnet I' and with the spring J' and a contact-piece i' . From the contact-piece i' a wire C^{22} extends to one end of the coil of the magnet s^2 . A wire C^{23} extends from the other end of the coil of this magnet to one end of the coil of the magnet s^6 . From the other end of the latter a wire C^{24} extends to one end of the coil of the magnet S^5 . The other end of the coil of this magnet is connected by a wire C^{25} with the same coil of the transformer K^3 as that from which the wire C^{20} extends. In this example of my improvement there is a main circuit and an independent circuit supplying electricity derived from the first-mentioned circuit to the signal through the medium of transformer K^3 . From a main circuit electricity is also supplied to an independent track-circuit through medium of transformer K' . Of course there may be any number of such track-circuits. An independent dynamo or batteries may obviously be employed for supplying the track-circuits. In this example, as in my former examples, if a direct-current dynamo be used a direct-current

transformer or motor-dynamo would be preferable. In other cases the ordinary alternating transformer will suffice.

In Fig. 3 I have shown a modification of my invention, in which I have connected my transformers with my dynamo B in multiple arc. The other connections are very similar to those in Fig. 2, except that I have in the present figure shown the system as applying to a double-track railroad. Referring to the drawings, B represents a dynamo of any ordinary or suitable construction, from which extend wires to supply electricity to the various sections of the system, here represented as wires C²⁶ and C²⁷. These wires may extend the length of the system, and wherever necessary power is supplied to local transformers, here represented as K⁴ K⁵ K⁶ K⁷, which are connected to the main supply-wires C²⁶ and C²⁷ by wires C²⁸ and C²⁹, C³⁰ and C³¹, C³² and C³³, C³⁴ and C³⁵, respectively.

I may remark here that the transformers K⁴ and K⁶ are intended to supply power to operate the signals protecting the track-circuits of the track-sections a², a³ respectively, which form with the track-section a' the railway-track A, on which trains are indicated to traverse in the direction indicated by the arrow W. K⁵ and K⁷ are transformers intended to supply power to the rails of the track-sections a² and a³, respectively. These transformers as well as the dynamo B may be of any of the ordinary types; but if a direct-current dynamo be used it would be preferable to use a dynamotor (sometimes called a "motor-dynamo") or direct-current transformer. In other cases the alternating transformer or any other kind may be used. The wires C³⁶ C³⁷ C³⁸ C³⁹ and the coils of the cautionary signal S⁷ and the danger-signal S⁸, together with the contact-piece i³ of the circuit-changer H³ and that coil of the transformer K⁴ which is not connected by the wires C²⁸ C²⁹ with the wires C²⁶ C²⁷, form a local circuit controlling the signals protecting the track-section a'. The signals S⁷ and S⁸ may be similar to the other signals heretofore described and the circuit-changer H³ with its contact-piece may also be similar to others described heretofore. The wires C⁴⁰, C⁴¹, C⁴², and C⁴³ and the coils of the cautionary signal S⁹ and the danger-signal S¹⁰, together with the contact-piece i⁴ of the circuit-changer H⁴ and that coil of the transformer K⁶ which is not connected by the wires C³² and C³³ to the wires C²⁶ and C²⁷, form a local circuit controlling the signals protecting the track-section a³. The high-potential coil of the transformer K⁵ is connected by wires C³⁰ and C³¹ to the wires C²⁶ C²⁷, and the low-potential coil of this transformer is connected by wires C⁴⁴ C⁴⁵ with the rails of the track-section a², the opposite ends of the rails of this section being connected with the coil of the circuit-changer H³. The high-potential coil of the transformer K⁷ is connected by wires C³⁴ C³⁵ to the wires C²⁶ C²⁷ and the low-potential coil of this transformer is connected by

wires C⁴⁶ C⁴⁷ with the rails of the track-section a³, the opposite ends of the rails of this section being connected with the coil of the circuit-changer H⁴. The signals S⁹ and S¹⁰ may be similar to the other signals heretofore described and the circuit-changer H⁴ with its contact-piece i⁴ may also be similar to others described heretofore. The cautionary signal S⁷ is intended to be located in proximity to the track-sections a' at some considerable distance from the meeting ends of the track-sections a' a². The danger-signal S⁸ and the cautionary signal S⁹ are intended to be located in proximity to the meeting ends of the track-sections a' a³. The danger-signal S¹⁰ is intended to be located in proximity to the meeting ends of the track-sections a² a³. In this example of my improvement it will be seen that all my transformers are connected to the main supply-wires C²⁶ and C²⁷ in multiple arc.

Fig. 4 is similar to Fig. 3, with the exception that track-batteries L' L² are used in place of the transformers K⁵ and K⁷, respectively, for supplying the track-circuits a² a³, respectively.

In Fig. 5 I have illustrated my invention as applied to a single-track railroad having two sets of signaling devices for trains running in reverse directions. In this figure A designates a track composed of track-sections a' a² a³ a⁴ a⁵. B³ designates a dynamo connected through one of its poles or electrodes to the ground by a wire C⁸⁴, represented as extending to the ground-plate G³. The other pole or electrode of the dynamo has a wire C²⁶ connected to it. From the wire C²⁶ a wire C²⁷ extends to a resistance device E', and a wire C²⁸ extends from the wire C²⁶ to one end of the coil of the electromagnet s⁶ belonging to a cautionary signal S¹¹. This signal is fulcrumed between its ends upon a pin t⁶ and has combined with it a weight u⁷. Preferably the magnet s⁶ will be of the solenoid type or one affording a long range of movement. It is intended that the magnet shall normally hold the signal in the position indicative of safety, and that whenever the magnet is de-energized the weight will adjust the signal to indicate danger. All the signals in my system may operate in this manner. From the other end of the coil of the electromagnet s⁶ a wire C²⁹ extends to a circuit-changer H⁵, represented as consisting of a pivoted lever, the wire C²⁹ extending to the pivot of the lever. The circuit-changer lever H⁵ coacts with a contact-piece i⁵, from which a wire C³⁰ extends to one end of the coil of an electromagnet s⁷ belonging to a danger-signal S⁷. The circuit-changer H⁵ has combined with it a spring J³ for moving it away from the contact-piece i⁵ and a magnet I³ for moving it to the said contact-piece. The ends of the coil of the magnet I³ are connected with the adjacent ends of the rails comprised in the track-section a². The signal S⁷ is fulcrumed to a pin t⁸ and combined with a weight u⁸. From the resistance

device E' a wire C³¹ extends. In this example of my improvement the wire C³¹ connects directly with the transformer K⁸ and also communicates directly with a wire C³² leading to 5 one end of the coil of the electromagnet s⁸ belonging to the cautionary signal S⁸. The other end of the coil of the electromagnet s⁸ is connected by a wire C³³ with a circuit-changer H⁶. The signal S⁸ is fulcrumed between its ends 10 to a pin t⁹ and combined with a weight u⁹. From the transformer K⁸ a wire C³⁴ extends. This transformer is connected with the adjacent ends of the rails comprised in the track-sections a². The low-potential coils of the 15 transformer will be connected with these rails and the high-potential coil with the wires C³¹ C³⁴. From the other end of the coil of the magnet s⁷ belonging to the danger-signal S⁷ a wire C³⁵ extends to one end of a coil of a magnet s⁹ belonging to a danger-signal S⁹, arranged on the opposite side of the track A. This signal is fulcrumed between its ends to a pin t¹⁰ and combined with a weight u¹⁰. From the other end of the coil of the electromagnet s⁹ belonging to the danger-signal S⁹ a wire C³⁶ extends to one end of the coil of an electromagnet s¹⁰ belonging to a signal S¹⁰. The signal S¹⁰ is fulcrumed between its ends to a pin t¹¹ and combined with a weight u¹¹. 20 From the other end of the coil of the magnet s¹⁰ a wire C³⁷ extends to a wire C³⁴. The wire C³⁴ extends to one end of the high-potential coil of a transformer K⁴, the ends of whose low-potential coil are connected with the adjacent ends of the rails comprised in the track 25 a³. The other ends of the rails are connected by wires with the ends of the coil of an electromagnet I⁴, which is combined with the circuit-changer H⁶. A spring J⁴ is also combined with this circuit-changer. This circuit-changer coacts with a contact-piece i³.

From the contact-piece i³ a wire C³⁸ extends to one end of the coil of a magnet s¹¹ belonging to a danger-signal S¹². The signal S¹² is fulcrumed to a pin t¹² and combined with a weight u¹². From the other end of the coil of the magnet s¹¹ a wire C³⁹ extends to one end of the coil of an electromagnet s¹³ belonging to a danger-signal S¹⁴. From the wire C³⁴ a wire C⁴⁰ extends to one end of the coil of an electromagnet s¹² belonging to a cautionary signal S¹³. This signal S¹³ is fulcrumed upon a pin t¹³ and combined with a weight u¹³. A wire C⁴¹ extends from the other end of the coil of the magnet s¹² to a circuit-changer H⁴, which coacts with a contact-piece i⁴ and has combined with it a spring J⁵ and a magnet I⁵. This magnet I⁵ has the ends of its coil connected with the rails comprised in 30 the track-section a⁴, the other ends of these rails being connected with the ends of the low-potential coil of the transformer K⁴. From the high-potential coils of the transformer K⁴ a wire C⁴² extends to one extremity of the 35 high-potential coil of the transformer K⁵. The other end of the high-potential coil of the latter transformer is shown as connected

to a wire C⁴³, which is represented as extending to a ground-plate G⁴. From the other end of the coil of the electromagnet s¹³ belonging to the signal S¹⁴ a wire C⁴⁴ extends to and connects with one of the ends of the coil of an electromagnet s¹⁴ belonging to a cautionary signal S¹⁵. This signal is fulcrumed between its ends to a pin t¹⁴ and combined with a weight u¹⁴. From the other end of the coil of the magnet s¹⁴ a wire C⁴⁵ extends to the wire C⁴². From the contact-piece i⁴ a wire C⁴⁶ extends to one end of the coil of an electromagnet s¹⁵ belonging to a danger-signal S¹⁶, which is fulcrumed between its ends to a pin t¹⁵ and combined with a weight u¹⁵. From the other end of the coil of the electromagnet S¹⁶ a wire C⁴⁷ extends to one end of the coil of an electromagnet s¹⁶ belonging to a danger-signal S¹⁶, which is fulcrumed between its ends to a pin t¹⁶ and combined with a weight u¹⁶. From the other end of the coil of the electromagnet of the signal S¹⁶ a wire C⁴⁸ extends to one end of the coil of an electromagnet s¹⁷ belonging to a cautionary signal S¹⁷, which between its ends is fulcrumed to a pin t¹⁷ and has combined with it a weight u¹⁷. From the other end of the coil of the magnet s¹⁷ a wire C⁴⁹ extends to the wire C⁴³.

To facilitate an understanding of the different branch circuits comprised in the main circuit, I have delineated certain wires differently. It will be observed that the signals S¹¹ S⁷ S⁸ S¹² S¹³ S³⁴ are on one side of the track and that the signals S⁹, S¹⁰, S¹⁴, S¹⁵, S¹⁶, and S¹⁷ are on the other side of the track. These two series of signals are intended for trains running in opposite directions. The signals S¹¹, S⁷, S⁸, S¹², S¹³, and S³⁴ are intended for trains running in the direction indicated by the arrow W¹, and the signals S⁹, S¹⁰, S¹⁴, S¹⁵, S¹⁶, and S¹⁷ for trains running in the direction indicated by the arrow W². The signal S¹¹ is intended to be located adjacent to the track-section a' at some considerable distance from the meeting ends of the track-sections a' a². The signals S⁷ S⁸ are intended to be located adjacent to the meeting ends of these track-sections a' a². The signals S¹² S¹³ are intended to be located adjacent to the meeting ends of the track-sections a² a³. The signal S³⁴ is intended to be located adjacent to the meeting ends of the track-sections a³ a⁴. The signal S¹⁷ is intended to be arranged adjacent to the track-section a⁵ at a considerable distance from the track-section a⁴. The signals S¹⁵ S¹⁶ are intended to be located adjacent to the meeting ends of the track-sections a⁴ a⁵ and the signals S¹⁰ S¹⁴ are intended to be located adjacent to the ends of the track-sections a³ a⁴. The signal S⁹ is intended to be located adjacent to the meeting ends of the track-sections a² a³.

It will be seen that in this example of my improvement, as well as in the one previously described, all the signals are supplied from a common source and in this example are in a single main circuit. It will also be observed

that in this example of my improvement I have represented practically independent track-circuits.

I do not wish to be confined to the use of 5 transformers $K^4 K^5$. As already illustrated in connection with a former example of my improvement, the track-circuits may be supplied with electricity from batteries, or, if so desired, from an independent dynamo-electric machine giving a circuit of low potential. 10 Normally the electromagnets $I^3 I^4 I^5$ will be in the track-circuit, and consequently energized. This is represented in connection with the magnets $I^3 I^5$ belonging to the track-sections $a^2 a^4$. 15

T' is an arbitrary representation of a train located upon the track-section a^3 . As represented, this short-circuits out the magnet I^4 , and, by deenergizing such magnet, causes the 20 circuit-changer H^3 to interrupt the communication between the wires $C^{33} C^{38}$. This has the effect of deenergizing the magnet belonging to the danger-signal S^{12} and that belonging to the danger-signal S^{14} , which are located 25 adjacent to the different ends of the track-section a^3 . It will also have the effect of deenergizing the magnets belonging to the cautionary signals $S^8 S^{15}$, located, respectively, adjacent to the different ends of the track a^4 . 30 Manifestly a danger-signal and a cautionary signal are given in front of the train, and a danger-signal and a cautionary signal are given at the rear of the train, the danger-signal in each case being given at the end of 35 the track-section a^3 and the cautionary signal at the distant end of the next adjacent track-section in each direction. Thus safety will be insured to trains running in opposite directions or in the same direction upon a single 40 track.

Turning now to Fig. 6, $A' A^2$ designate two parallel tracks for trains running in the same direction. Each of these tracks comprises a number of electrically independent track-sections $a' a^2 a^3 a^4$. B^4 is a dynamo-electric 45 machine having one of its poles or electrodes connected by a wire C^{50} with a ground-plate G^5 and its other pole or electrode connected with a wire C^{51} , leading to a resistance device 50 E^2 . From the resistance device E^2 a wire C^{52} extends to one extremity of the high-potential coil of a transformer K^9 , the ends of whose low-potential coils connect with the adjacent 55 ends of the rails comprised in the track-section a^3 of the track A' . From the other end of the high-potential coil of this transformer a wire C^{53} extends to one extremity of the high-potential coil of a transformer K^{10} , the 60 ends of whose low-potential coils are connected with the adjacent ends of the rails comprised in the track-section a^2 of the track A^2 . From the other extremity of the high-potential coil of the transformer K^{10} a wire 65 C^{54} extends to one extremity of the high-potential coil of a transformer K^{11} , the ends of whose low-potential coil are connected with the adjacent ends of the rails comprised in

the track-section a^3 of the track A' . From the other extremity of the high-potential coil of the transformer K^{11} a wire C^{55} extends to 70 one extremity of a high-potential coil of a transformer K^{12} , the ends of whose low-potential coil are connected with the adjacent ends of the rails comprised in the track-section a^3 of the track A^2 . From the other extremity of the high-potential coil of the transformer K^{12} a wire C^{56} extends to a ground-plate G^6 . 75

The track-section a^2 of the track A' has those ends of its rails which are more distant 80 from the transformer K^9 connected with the ends of the coil of an electromagnet I^6 , which is combined with a circuit-changer H^6 . The track-section a^2 of the track A^2 has those ends of its rails which are the more distant from 85 the transformer K^{10} connected with the ends of the coil of an electromagnet I^7 , which is combined with the circuit-changer H^7 . The track-section a^3 of the track A' has those ends of its rails which are the more distant from 90 the transformer K^{11} connected to the ends of the coil of an electromagnet I^8 , which is combined with a circuit-changer H^8 . The track-section a^3 of the track A^2 has those ends of its rails which are the more distant from 95 the transformer K^{12} connected with the ends of the coil of an electromagnet I^9 , which is combined with a circuit-changer H^9 . The circuit-changer H^6 has combined with it a spring J^6 and coacts with a contact-piece i^6 . The circuit-changer H^7 is combined with a spring J^7 100 and coacts with a contact-piece i^7 . The circuit-changer H^8 is combined with a spring J^8 and coacts with a contact-piece i^8 . The circuit-changer H^9 is combined with a spring J^9 105 and coacts with a contact-piece i^9 .

S^{18} is a cautionary signal arranged adjacent to the section a' of the track A' at a considerable distance from the section a^2 thereof. It is fulcrumed between its ends upon a pin 110 t^{18} and combined with a magnet s^{18} and a weight u^{18} .

S^{19} is a danger-signal, and S^{20} is a cautionary signal. These two signals are arranged close to the meeting ends of the track-sections $a' a^2$ of the track A' . The signal S^{19} is fulcrumed to a pin t^{19} and combined with a magnet s^{19} and a weight u^{19} and the signal S^{20} is fulcrumed to a pin t^{20} and combined with a magnet s^{20} and a weight u^{20} . 120

S^{21} is a danger-signal arranged adjacent to the meeting ends of the track-sections $a^2 a^3$ of the track A' . It is fulcrumed between its ends to a pin t^{21} and combined with a magnet s^{21} and a weight u^{21} . 125

A cautionary signal S^{22} is arranged adjacent in the track-section a' of the track A^2 at some distance from the track-section a^2 of this track. It is fulcrumed to a pin t^{22} and combined with a magnet s^{22} and a weight u^{22} . 130

S^{23} is a danger-signal, and S^{24} is a cautionary signal. These signals are arranged adjacent to the meeting ends of the track-sections $a' a^2$ of the track A^2 . The signal S^{23} is fulcrumed

on a pin t^{23} and combined with a magnet s^{23} and a weight u^{23} . The signal S^{24} is fulcrumed upon a pin t^{24} and combined with a magnet s^{24} and a weight u^{24} .

5 S^{25} is a danger-signal arranged adjacent to the meeting ends of the track-sections $a^2 a^3$ of the track A^2 . It is fulcrumed on a pin t^{25} and combined with a magnet s^{25} and a weight u^{25} .

From the wire C^{51} a wire C^{57} extends to one end of the coil of the magnet s^{18} belonging to the signal S^{18} . From the other end of the coil of this magnet a wire C^{58} extends to the circuit-changer H^6 . A wire C^{59} extends from the contact-piece i^6 to one end of the coil of the magnet s^{19} belonging to the signal S^{19} . The other end of the coil of this magnet is connected by a wire C^{60} with a wire C^{52} just beyond the resistance device E^2 . A wire C^{61} extends from the wire C^{52} and connects with one end of the coil of the magnet s^{20} belonging to the signal S^{20} . The other end of the coil of this magnet is connected by a wire C^{62} with the circuit-changer H^8 . The wire C^{63} extends from the contact-piece i^8 to one end of the coil of the magnet s^{21} belonging to the signal S^{21} . The other end of the coil of this magnet is connected by a wire C^{64} with the wire C^{54} . A wire C^{65} extends from the wire C^{51} and connects with one end of the coil of the magnet s^{22} belonging to the signal S^{22} . The other end of the coil of this magnet is connected by a wire C^{66} with the contact-piece i^7 . From the circuit-changer H^7 a wire C^{67} extends to one end of the coil of the magnet s^{23} belonging to a signal S^{23} . The other end of the coil of this magnet is connected by a wire C^{68} with the wire C^{52} . A wire C^{69} extends from the wire C^{52} and connects with the coil of the magnet s^{24} belonging to the signal S^{24} . The other end of the coil of this magnet is connected by a wire C^{70} with the contact-piece i^7 . From the circuit-changer H^9 a wire C^{71} extends to one end of the coil of the magnet s^{25} belonging to the signal S^{25} . From the other end of the coil of this magnet a wire C^{72} extends and connects with the wire C^{54} .

Normally the signals will be held in the "safety" position by the electric current. 50 When a train, car, or locomotive passes over any track-section, it short-circuits out the magnet belonging to that track-section and causes the signals which are controlled by said magnet to indicate danger. Arbitrary representations $T^2 T^3$ of trains are located 55 on the track-sections a^3 of the tracks $A' A^2$, and as a consequence the circuit-changers $H^8 H^9$ are shown as removed from their contact-pieces $i^8 i^7$. The adjustment of these 60 circuit-changers into the position in which they are represented causes the cautionary signal S^{20} and the danger-signal S^{21} belonging to the track A' to be shifted to indicate danger, and also causes the cautionary signal S^{24} and the danger-signal S^{25} belonging to the track A^2 to indicate danger.

Although I have shown the signals as connected in series, they might obviously be connected in multiple arc. Obviously the transformers might be dispensed with and 70 batteries substituted, as illustrated in connection with a former-described example of my improvement. I will also remark that if a direct-current dynamo be used a dynamo- 75 tor or direct-current transformer would be preferable; but in other cases the ordinary alternating-current transformer would suffice.

It will be seen that in this last-described 80 example of my improvement all the signals are supplied with electricity from a common source through a main circuit including them, and that practically independent track-circuits are employed.

In Fig. 7, A designates a track comprising 85 track-sections $a' a^2 a^3 a^4$. A^3 is another track crossing the former at right angles and comprising track-sections $a' a^2 a^3 a^4$. Between the opposite extremities of the sections $a^2 a^3$ of the two tracks A' and $a^2 a^3$ of the track A^3 90 a frog A^4 is arranged. This frog is not electrically connected with any of the other parts of the system. B designates a dynamo having one pole or electrode connected by a wire C' with a ground-plate G' and its other pole or electrode connected with a wire C^2 , which extends to the extremity of the high-potential coil of a transformer K' , the other end of said coil being connected with a wire C^{85} , leading to one extremity of the high-potential 95 coil of a transformer K^2 , whose other end is connected by a wire C^{73} with the ground-plate G^2 . The track-section a^2 of the track A' and the track-section a^3 of the track A^3 are electrically connected by wires or their equivalents. 100 This is true of the track-section a^3 of the track A' and the track-section a^2 of the track A^3 . The extremities of the low-potential coil of the transformer K' are connected with the adjacent ends of the rails of the track-section 105 a^2 of the track A' . The ends of the track-section a^3 of the track A^3 which are distant from the track-section a^2 of the track A' are connected with a magnet I' , which has combined with it a circuit-changer H' , a contact-piece i' , and a spring J' . The extremities of 110 the low-potential coil of the transformer K^2 are connected with the adjacent ends of the rails comprised in the track-section a^3 of the track A' , the opposite ends of the rails of this 115 section being connected with the rails of the diagonal adjoining track-section a^2 of the track A^3 . The ends of the track-section a^2 of the track A^3 which are distant from the track-section a^3 of the track A' are connected with 120 one end of the coil of the magnet I^2 , having combined with it a circuit-changer H^2 , a contact-piece i^2 , and a spring J^2 . From the wire C^2 a wire C^{74} extends to one end of the coil of 125 the magnet s^{26} belonging to a cautionary signal S^{26} , which is pivoted to a pin t^{26} and combined with a weight u^{26} . This signal is ar- 130

ranged adjacent to the track-section a' of the track A' at some distance from the track-section a^3 thereof. From the other end of the coil of the magnet s^{26} a wire C^{36} extends to 5 one end of the magnet s^{28} belonging to a danger-signal S^{27} . This danger-signal is pivoted to a pin t^{27} and combined with a weight u^{27} . This signal is intended to be located adjacent to the meeting ends of the rails comprised in 10 the track-sections $a' a^3$ of the track A' . The signals $S^{26} S^{27}$ are intended for trains traveling the track A' in the direction indicated by the arrow W' . From the other end of the coil of the magnet s^{28} a wire C^{35} extends to 15 the circuit-changer H' . From the contact-piece i' a wire C^{36} extends to one end of the coil of the magnet s^{29} belonging to a cautionary signal S^{28} , arranged adjacent to the section a^3 of the track A^3 at some distance from 20 the track-section a^3 of the latter. The signal S^{28} is fulcrumed between its ends to a pin t^{28} and combined with a weight u^{28} . From the other end of the coil of the magnet s^{29} a wire C^{37} extends to 25 one end of the coil of a magnet s^{27} belonging to a danger-signal S^{29} , which latter is arranged adjacent to the meeting ends of the track-sections $a^4 a^3$ of the track A^3 . The signal S^{29} is pivoted to a pin t^{29} and combined with a weight u^{29} . The signals $S^{28} S^{29}$ 30 are intended for trains moving in the direction of the arrow W^2 along the track A^3 .

From the magnet s^{27} a wire C^{38} extends to the circuit-changer H^2 . From the contact-piece i^2 belonging to the circuit-changer H^2 a 35 wire C^{39} extends to one end of the coil of a magnet s^{31} belonging to a danger-signal S^{31} . This signal is pivoted to a pin t^{30} and combined with a weight u^{30} . From the other end of the coil of the magnet s^{31} a wire C^{30} extends to 40 one end of the coil of a magnet s^{32} belonging to a cautionary signal S^{30} . This signal S^{30} is pivoted to a pin t^{31} and combined with a weight u^{31} . The signals $S^{31} S^{30}$ are intended for trains running along the track A^3 in the direction 45 of the arrow W^3 . From the other end of the coil of the magnet s^{32} a wire C^{31} extends to one end of the coil of a magnet s^{33} belonging to a danger-signal S^{32} . This signal is pivoted to a pin t^{32} and combined with a weight u^{32} . 50 From the other end of the coil of the magnet s^{33} a wire C^{32} extends to one end of the coil of a magnet s^{34} belonging to a cautionary signal S^{33} . This signal is pivoted to a pin t^{33} and combined with a weight u^{33} . From the other 55 end of the coil of the magnet s^{34} a wire C^{33} extends to the wire C^{38} . Preferably the branch of the main circuit containing the magnets of the various signals will be substantially of the same resistance as the other branch, the 60 other branch containing the high-potential coils of the transformers $K' K^2$. The signals $S^{32} S^{33}$ are intended for trains traveling on the track A' in the direction of the arrow W^4 . Obviously, in this example of my invention, 65 the branch of the main circuit comprising the signals might be supplied with current through a transformer, as illustrated in Fig.

7, and the track-sections by batteries. Obviously all the sections of tracks on opposite sides of the frog A^4 will be thoroughly protected by the system of signals illustrated in the last-described example of my improvement regardless of the direction in which trains may be running on either of the tracks. 70

In using the term "step-down transformer" 75 I refer to that type of transformer in which a reduction in the voltage of the secondary circuit is effected relatively to that of the primary or dynamo circuit. The amount of current, or, in other words, the number of amperes in the secondary circuit, may be regulated to any desired quantity. 80

What I claim as my invention, and desire to secure by Letters Patent, is—

1. In electrical signaling apparatus for railways, the combination of a dynamo driven by power, a series of electrically-operated and electrically-controlled semaphore-signals, a series of transformers, one at each block for transforming the current derived from the 90 dynamo to one of low potential, a low-potential circuit formed of the secondary winding of the transformer, the track-rail, and either the wheels and axles of the train or the relay at block, and electrical connections, substantially as shown and described. 95

2. In a block-signal, the combination of the primary circuit the transformer and secondary circuit, the track-circuit taking the current from the secondary circuit of the transformer at one signal, the relay placed in the track-circuit at the preceding signal, the signal-operating motor controlled by the relay, and the signal operated by the motor, substantially as specified. 100

3. In a railway signal system, the combination of a dynamo, a distribution system extending therefrom, transformers having the primary circuits connected to the distribution system, the secondary circuits being connected to the tracks of the block, and track-circuit relays arranged to control the signals of the system. 110

4. In a railway signal system comprising a number of blocks or sections, the combination of a dynamo, a distribution system extending therefrom, transformers having their primary coils connected to the distribution system, the secondary coils being connected to the circuits containing the signals, and devices along the blocks or sections for controlling the signal-circuits, substantially as specified. 115

5. In a railway signal system comprising a number of blocks or sections, the combination of a dynamo, circuit-wires extending therefrom, transformers for the blocks or sections, having their primary circuits connected to the dynamo circuit-wires, signals for the said blocks or sections arranged in the secondary circuits of the transformers, track-circuits comprising the rails of the blocks or sections, and track-circuit relays, arranged to disconnect or control the secondary cir- 120

13

- cuits of the transformers for operating the signals, substantially as specified.
6. In a railway signal system comprising a number of blocks or sections, the combination of a dynamo, circuit-wires extending therefrom, transformers for the blocks or sections, having their primary circuits connected to the dynamo circuit-wires in multiple, signals for the said blocks or sections arranged in the secondary circuits of the transformers, track-circuits comprising the rails of the blocks or sections, and track-circuit relays, arranged to disconnect or control the secondary circuits of the transformers for operating the signals, substantially as specified.
7. In a railway signal system comprising a number of blocks or sections, the combination of a dynamo, circuit-wires extending therefrom, two sets of transformers for the blocks or sections, having their primary circuits connected to the dynamo circuit-wires, signals for the said blocks or sections, arranged in the secondary circuits of one of the two sets of transformers, track-circuits connected with the secondary circuits of the other set of transformers, and track-circuit relays arranged to disconnect or control the secondary transformer-circuits containing the signals, substantially as specified.
8. In a railway signal system comprising a number of blocks or sections, the combination of a dynamo, circuit-wires extending therefrom, two sets of transformers for the blocks or sections, having their primary circuits connected to the dynamo circuit-wires in multiple, signals for the said blocks or sections, arranged in the secondary circuits of

one of the two sets of transformers, track-circuits connected with the secondary circuits of the other set of transformers, and track-circuit relays arranged to disconnect or control the secondary transformer-circuits containing the signals, substantially as specified.

9. In a railway signal system comprising a number of blocks or sections, the combination of a dynamo, high-tension circuit-wires extending therefrom, step-down transformers having their primary coils connected to the high-tension circuit-wires, signal-circuits for the blocks or sections connected to the secondary coils of the transformers, track-circuits comprising the rails of the blocks or sections and receiving a current of low tension from the secondary coils of the transformers and relays in the track-circuits for disconnecting or controlling the secondary circuits containing the signals, substantially as specified.

10. In a railway signal system comprising a number of blocks or sections, the combination of a dynamo, a distribution system extending therefrom, transformers having their primary coils connected to the distribution system, the secondary coils being connected to the rails of the blocks or sections, and track-circuit relays arranged to disconnect or control the signals of the system, substantially as specified.

In testimony whereof I have signed my name to this specification in the presence of two subscribing witnesses.

WILLIAM G. ROOME.
